UNITED STATES PATENT OFFICE.

ANNIE B. HOPKINS, OF LEWISTOWN, MONTANA.

DESIGN FOR A BUTTON.

51,122.

Specification for Design.

Patented Aug. 7, 1917.

Application filed June 11, 1917. Serial No. 174,149. Term of patent 3½ years.

To all whom it may concern:

Be it known that I, ANNIE B. HOPKINS, a citizen of the United States, residing at Lewistown, in the county of Fergus and State of Mont., have invented a new, original, and ornamental Design for Buttons, of which the following is a specification, reference being had to the accompanying drawing, forming part thereof.

The figure is a plan view of a button, showing my new design.

I claim:—

The ornamental design for a button, as shown.

ANNIE B. HOPKINS.

Witnesses:

E. K. MATSON,
C. E. DUNN.
